Atty.

UNITED STATES PATENT OFFICE

FRANK A. ZIBELMAN, OF CHICAGO, ILLINOIS

DUPLICATOR

Application filed May 26, 1927. Serial No. 194,363.

The invention relates to duplicators, more particularly to that form of duplicator in which a negative or reverse impression of matter to be copied is impressed upon an adhesive duplicating surface, and positive impressions taken therefrom by bringing sheets of paper or the like in contact therewith.

Heretofore, in stripping the paper from the adhesive duplicating surface, it was necessary for the operator to hold one edge thereof and to draw the same upwards and away from the adhesive duplicating surface to strip the sheet of paper therefrom. It is the main object of this invention to provide novel and improved means for automatically stripping the sheet of paper from the adhesive duplicating surface after said sheet has had an impression taken thereon from said duplicating surface.

A further object of this invention is to provide simple, efficient and economic means whereby the rapid handling of sheets of paper and the automatic stripping of the same from the adhesive duplicating surface of the duplicator is facilitated.

A still further object of this invention consists in the novel combination, arrangement and construction of various devices, elements and parts, as set forth in the claims hereof, one embodiment of the same being illustrated in the accompanying drawings and described in this specification.

In the said drawings:

Fig. 1, is a top plan view of one side of a duplicator of the character described with my invention embodied therein;

Fig. 2, is a longitudinal section of the same; and

Fig. 3, is a detailed view to be hereinafter described.

In carrying my invention into effect in the embodiment thereof, which I have selected for illustration in the accompanying drawings, and description in this specification, I provide a main frame structure of any form suitable for the purpose, such as may comprise a pair of end frame members 1, suitably connected by means of tie rods 2, or the like, so as to make a frame of sufficient rigid construction. A bed 3, secured between

said frame members, comprises or serves as a support for an adhesive duplicating surface 4. This adhesive duplicating surface may be either the surface of the bed itself, or a portion of a film or strip secured to the bed, or there may be, if desired, a comparatively long sheet, the portions of which not in use may be stored upon rollers journaled in said frame members, according to a construction which is well understood in the art to which said duplicators relate. As the means for the storage of the film and for winding and unwinding the same therefrom and passing the same over the support, as the bed 3, form no part of the present invention, it is not necessary to describe the same in detail.

On each of the side tie rods 2, is mounted a sliding member 6, said member having an upwardly extending portion 7, said portion lying above the plane of the bed 3. Journaled in said side members 6, are the ends of a shaft 8, said shaft having rotatably mounted thereon a roller 9, adapted to depress a sheet of paper 10 upon the adhesive duplicating surface 11. A rack 12 is mounted on the bed 3, at each side thereof, said rack extending across the full length of said bed. The roller 9, is provided near each end thereof with a pinion or tooth wheel 13 for engaging the teeth in the rack 12. The upper portions of the side members 6 may be joined together by a connecting rod or handle 14, for convenience in operating the same.

Each of the sliding side members 6 is provided with an elongated bearing 15, in which is received for sliding movement therein a rod 16, one end of said rod being screw-threaded and having a nut 17, threaded thereon to act as a stop, and the other end of said rod has secured thereto an upwardly and forwardly extending bracket 18, in the free ends of which is journaled the ends of a shaft 19, upon which is rotatably mounted a roller 20, said roller being positioned in a plane above the plane in which lies the roller 9, said rollers 9 and 20 being adapted for contacting engagement with each other, and when in such engagement the rollers are positioned so that the central axis of the roller

65

70

75

80

85

90

95

100

20 will be to the rear and above the central axis of the roller 9. The sides of the brackets 18 are connected by a connecting rod 21, so as to make of the same a frame of sufficient rigid construction. Pinions or toothed wheels are secured to the roller 20, near the ends thereof, said pinions being adapted for engagement with the pinions 13 provided on the roller 9, whereby said rollers when in 10 contacting engagement with each other, may rotate in unison. Springs 23 are provided on the rod 16 surrounding the same, one end of said spring bearing against the bracket 18, and the other end of said spring bearing against the bearing 15, said springs tending to normally move said brackets 18 away from the sliding members 6.

Secured to the upper portion 7, of the sliding member 6, on the inside thereof is a pivoted latch 24, said latch being pivoted intermediate the ends thereof and is adapted to engage a stud 25, provided on the bracket 18 and thereby couple the member 6 and brackets 18, together when desired. A leaf spring 26, secured to the member 7 above the latch 24, tends to depress the latch into engagement with said stud 25. A rod 27, is secured to the forward end frame 1 of the machine said rod having stops 28 thereon adapted when the sliding member 7 is moved up to the same, to swing the latch 24 about its pivot to elevate the same and disengage it from the stud 25.

The extreme rearward movement of the brackets 18, may be limited by their engagement with a portion of the end frame 1 (as shown in Fig. 2 of the drawings) or a stop means comprising a stud 29 secured to a portion of the end frame 1 may be provided for that purpose.

A sheet of paper 10 is shown in Fig. 1, most of which is lying flat upon the adhesive duplicating surface, but one end of which, indicated at 30, is shown raised up above the adhesive duplicating surface, and passing between the rollers 9 and 20. When moved to the right from the position shown in Fig. 1, the rollers 9 and 20, because of their contacting engagement with each other will strip 45 the sheet 10, from the adhesive duplicating surface, and cause the sheet to be fed upwardly and forwardly, until the sheet has been completely stripped its full length from the duplicating surface.

50 In the modification shown in Fig. 3, a bracket 18' is used in place of the bracket 18, said bracket 18' being provided at the forward end thereof with an elongated slot 31, which slots are adapted to receive the ends of the shaft 19 upon which is rotatably mounted the roller 20. The bracket 18' has a member 32 threaded therein, the inner end of said member being provided with a recess 33, and is adapted to be received in said 55 elongated slot 31. A pin 34 is positioned

in said recess, the free end of said pin engaging the shaft 19, said pin being held against said shaft by means of spiral spring 35 positioned in said recess 33, one end of said spring bearing against the inner wall of said recess 70 and the other end of said spring bearing against the end of said pin 34. It will thus be obvious that by threading the members 32 inwardly or outwardly the amount of pressure exerted by said pins 34 against the ends of the shaft 19 may be adjustably regulated. Because of the above construction it will be understood that the rollers 9 and 20 when in coupled position will be in yieldingly contacting engagement with each other. 75

In order to prevent the front edge 30 of the paper 10 from falling onto the adhesive duplicating surface 4, as the paper is being stripped therefrom by the rollers 9 and 20, the following mechanism is provided: A rod 80 40 is connected to the upper side portions 7, said rod being parallel to the rollers and lying directly in front of the depressing roller 9, and substantially on the level with the uppermost portion of the surface of the roller 9. Strips 41 of thin metal or the like have one 85 of their ends secured to the rod, and extend forwardly from said rod to the front of the machine, at which point they pass over rollers or pulleys 42 mounted on a rod 43 secured in the forward end frame 1 of the machine. To the lower free ends of the strips are connected weights 44 or the like, said weights being adapted to keep said strips taut at all 90 times. It will thus be noticed that with the construction above described, the front edge 30 of the sheet of paper, as it is being stripped from the duplicating surface, will ride on said strips and be kept from coming in contact with the adhesive duplicating surface 4. 95

The operation of the above described embodiment of my invention is as follows:

With the depressing roller 9, and stripping roller 20 in the positions shown in dotted lines in Fig. 2, of the drawings, a sheet of 100 paper is placed flat upon the adhesive duplicating surface, except that the back of the sheet, shown at 30, in Fig. 1, is prevented from falling upon the adhesive duplicating surface by means of the roller 20. As soon as 105 the paper has been laid upon the adhesive duplicating surface 11, the roller 9 is moved rearwardly to the position shown in full lines in Figs. 1 and 2 of the drawings, by means of the handle 14, the roller serving to depress the 110 paper firmly upon the adhesive duplicating surface. Upon the completion of the rearward movement of the roller 9, that is when it reaches the position shown in full lines 115 in Figs. 1 and 2 of the drawings, the latch 24 engages with the stud 25, locking the two rollers together and gripping the edge 30 of the sheet of paper 10 between the rollers. When moved forwardly from this position 120 the rollers 9 and 20 will be coupled together 125 130

and because of their contacting engagement with each other will cause the sheet of paper to be stripped from the adhesive duplicating surface and be fed upwardly and forwardly by said rollers, the edge 30 of the sheet riding on the strips 41, until the sheet is completely stripped from the duplicating surface. The feeding principle of the rollers 9 and 20 being very much like the principle of the paper feeding rolls employed in typewriting machines.

When the rollers 9 and 20 in their coupled position have reached the end of their forward movement the latches 24 will be engaged by the stops 28 causing said latches to swing about their pivots disengaging the studs 25, permitting the springs 23 to move the roller 20 rearwardly until the stop 17 on the rod 16 engages the bearing 15. If not already released the paper 10 will be released by the separation of the rollers 9 and 20, said paper being allowed to fall into a receptacle which may be provided therefor at the forward end of the machine. A new sheet of paper is then placed in position on the duplicating surface, and the operation repeated.

The advantages of my invention will be obvious from what has been said above concerning its construction and mode of operation, but some of them may be enumerated as follows: Owing to the elimination of unnecessary parts the apparatus is simple and inexpensive, while still efficient in operation; it is capable of rapid operation, the paper being stripped automatically from the adhesive duplicating surface, and the sheet of paper does not have to be held by the operator when the same is being stripped.

Having thus described my invention what I claim as new and desire to secure by Letters Patent is as follows:

1. In a duplicator, the combination with a supporting frame, a bed, and an adhesive duplicating surface upon said bed adapted to receive a sheet of paper; of a roller mounted on said duplicator and adapted to depress a sheet of paper upon said adhesive duplicating surface, a second roller mounted on said duplicator in a plane above that of the first roller, means adapted to couple said rollers together, means adapted to release said coupling means, and means mounted on said duplicator adapted for receiving the sheet of paper after an impression has been made thereon and for carrying away the same.

2. In a duplicator, the combination with a supporting frame, a bed, and an adhesive duplicating surface upon said bed adapted to receive a sheet of paper; of a roller rotatably and slidably mounted on said duplicator and adapted to depress a sheet of paper upon said adhesive duplicating surface, a second roller rotatably mounted on said duplicator in a plane above that of the first roller, means adapted to couple said rollers together,

means adapted to release said coupling means, means adapted to draw said second roller away from said first roller when the same are uncoupled, and means mounted on said duplicator adapted for receiving the sheet of paper after an impression has been made thereon and for carrying away the same.

3. In a duplicator, the combination with a supporting frame, a bed and an adhesive duplicating surface upon said bed adapted to receive a sheet of paper; of a roller rotatably mounted on said duplicator and adapted to depress a sheet of paper upon said adhesive duplicating surface, a second roller rotatably mounted on said duplicator and means adapted for coupling said rollers together, the central axis of the second-named roller lying in a plane above and to the rear of the central axis of the first named roller when the said rollers are in coupled condition, and means provided on said duplicator adapted for receiving the sheet of paper after an impression has been made thereon and for carrying away the same.

4. In a duplicator, the combination with a supporting frame, a bed, and an adhesive duplicating surface upon said bed adapted to receive a sheet of paper; of a roller rotatably mounted on said duplicator and adapted to depress a sheet of paper upon said adhesive duplicating surface, a second roller rotatably mounted on said duplicator in a plane above that of the first roller, means adapted for coupling said rollers together, said means causing said rollers to contact with each other throughout their length, means for causing the rotation of said rollers, when in coupled condition, and means mounted on said duplicator adapted for receiving the sheet of paper after an impression has been made thereon and for carrying away the same.

5. In a duplicator, the combination with a supporting frame, a bed, and an adhesive duplicating surface upon said bed adapted to receive a sheet of paper; of a roller rotatably mounted on said duplicator and adapted to depress a sheet of paper upon said adhesive duplicating surface, means on said roller for rotating the same, a second roller rotatably mounted on said duplicator in a plane above that of the first roller, means adapted to couple said rollers together, means on said second roller adapted when in coupled condition to engage said first named roller rotating means whereby said rollers may rotate together, means for releasing said coupling means, and means mounted on said duplicator adapted for receiving the sheet of paper after an impression has been made thereon and for carrying away the same.

6. In a duplicator, the combination with a supporting frame, a bed, and an adhesive duplicating surface upon said bed adapted to receive a sheet of paper; of sliding side mem-

bers mounted on said duplicator, a roller adapted to depress a sheet of paper upon said adhesive duplicating surface journaled in said side members, brackets slidably mounted in said side members, a second roller mounted in said brackets, said second roller lying in a plane above that of the first named roller, means adapted to couple said rollers together, and means mounted on said duplicator adapted for receiving the sheet of paper after an impression has been made thereon and for carrying away the same.

7. In a duplicator, the combination with a supporting frame, a bed, and an adhesive duplicating surface upon said bed adapted to receive a sheet of paper; of side members slidably mounted on said duplicator, a roller adapted to depress a sheet of paper upon said adhesive duplicating surface, journaled for rotation in said side members, brackets slidably mounted in said side members, a second roller rotatably mounted in said brackets, means adapted to couple said rollers together, said rollers being in yielding contacting engagement with each other, when in coupled condition, means adapted to release said coupling means, and means mounted on said duplicator adapted for receiving the sheet of paper after an impression has been made thereon and for carrying away the same.

8. In a duplicator, the combination with a supporting frame, a bed, and an adhesive duplicating surface upon said bed adapted to receive a sheet of paper; of side members slidably mounted on said duplicator, a roller rotatably mounted in said side members, said roller being adapted to depress a sheet of paper upon said adhesive duplicating surface, brackets slidably mounted in said side members, a second roller rotatably mounted in said brackets, means for normally holding said brackets spaced from said side members, means mounted on said side members for detachably engaging a portion of said brackets for bringing said first and second named rollers into an approximated and coupled position, said rollers being in yielding contacting engagement with each other, when in said coupled position, means for releasing said last mentioned means, and means mounted on said duplicator adapted for receiving the sheet of paper after an impression has been made thereon and for carrying away the same.

9. In a duplicator, the combination with a supporting frame, a bed, and an adhesive duplicating surface upon said bed adapted to receive a sheet of paper; of a roller rotatably mounted on said duplicator, and adapted to depress a sheet of paper upon said adhesive duplicating surface, a rack mounted on said bed, a pinion mounted on said roller adapted to mesh with said rack, a second roller rotatably mounted in said duplicator in a plane

above that of the first roller, a pinion mounted on said second roller adapted to mesh with the pinion on said first roller when said rollers are in coupled condition, means adapted to couple said rollers together, means adapted to release said coupling means, means adapted to automatically separate said rollers from each other, and means mounted on said duplicator adapted for receiving the sheet of paper after an impression has been made thereon and for carrying away the same.

10. In a duplicator, the combination with a supporting frame, a bed, and an adhesive duplicating surface upon said bed adapted to receive a sheet of paper; of a roller rotatably and slidably mounted on said duplicator and adapted to depress a sheet of paper upon said adhesive duplicating surface, a second roller slidably and rotatably mounted on said duplicator in a plane above that of the first roller, said second roller being adapted to hold a portion of said sheet of paper away from said adhesive duplicating surface, means adapted to couple said rollers together, means adapted to release said coupling means, means adapted to draw said second named roller away from said first-named roller when the same are uncoupled, and means mounted on said duplicator adapted for receiving the sheet of paper after an impression has been made thereon and for carrying away the same.

11. In a duplicator, the combination with a supporting frame, a bed, and an adhesive duplicating surface upon said bed, adapted to receive a sheet of paper; of side members slidably mounted on said duplicator, a roller rotatably mounted in said side members adapted to depress a sheet of paper upon said adhesive duplicating surface, a second roller adjustably mounted in said side member and normally spaced from said first roller, said second roller adapted to hold a portion of said sheet of paper away from said adhesive duplicating surface, means adapted to couple said rollers together with an edge of said sheet of paper held between them, and means mounted on said duplicator adapted for receiving the sheet of paper after an impression has been made thereon and for carrying away the same.

12. In a duplicator, the combination with a supporting frame, a bed, and an adhesive duplicating surface upon said bed adapted to receive a sheet of paper; of side members slidably mounted on said duplicator, a roller rotatably mounted in said side members adapted to depress a sheet of paper upon said adhesive duplicating surface, an elongated bearing provided in said side members, a rod slidably mounted in said bearing, a stop means on one end of said rod, a bracket on the other end of said rod, spring means provided between said bearing and bracket for normally holding said bracket away from

5 said bearing, a second roller rotatably mounted in said brackets, said roller lying in a plane above that of the first roller, means adapted to couple said brackets and side members together for bringing said rollers in contact with each other, and means for releasing said coupling means.

13. In a device of the character described the combination with an adhesive duplicating surface of a pair of rollers, one of said rollers adapted to depress a sheet of paper upon said adhesive duplicating surface, the other of said rollers lying in a plane above that of the first roller, means for detachably holding said rollers in contacting engagement with each other, means for releasing said last mentioned holding means, means adapted to draw one of said rollers away from the other upon the release of said holding means, and means mounted on said duplicator adapted for receiving the sheet of paper after an impression has been made thereon and for carrying away the same.

14. In a duplicator, the combination with a supporting frame, a bed, and an adhesive duplicating surface upon said bed adapted to receive a sheet of paper; of slidable side members mounted on said duplicator, a roller rotatably mounted in said side members adapted to depress a sheet of paper upon said duplicating surface, a second roller mounted on said side members in a plane above that of the first roller, said second roller adapted to hold a portion of said sheet of paper away from said adhesive duplicating surface, means adapted to couple said rollers together, and to hold the same in contact with each other throughout their length, whereby upon the rotation of said rollers the sheet of paper will be stripped from said adhesive duplicating surface and fed upwardly and forwardly by said rollers, means adapted to release said coupling means, and means mounted on said duplicator adapted for receiving the sheet of paper after an impression has been made thereon and for carrying away the same.

15. In a device of the character described the combination with an adhesive duplicating surface of a pair of rollers adapted to contract with each other throughout their full length when in coupled position, the central axis of one of said rollers lying above and to the rear of the central axis of said other roller when said rollers are in contact with each other, means normally holding said rollers spaced from each other, means adapted to couple said rollers together, means adapted to release said coupling means, and means mounted on said duplicator adapted for receiving the sheet of paper after an impression has been made thereon and for carrying away the same.

16. In a duplicator, the combination with a supporting frame, a bed, and an adhesive

duplicating surface upon said bed, adapted to receive a sheet of paper; of a roller rotatably and slidably mounted on said duplicator adapted to depress a sheet of paper upon said duplicating surface, a second roller lying in a plane to the rear and above that of the first roller cooperating with said first roller for automatically stripping said sheet of paper from said adhesive duplicating surface, and means mounted on said duplicator adapted for receiving the sheet of paper after an impression has been made thereon and for carrying away the same.

17. In a duplicator, the combination with a supporting frame, a bed, an adhesive duplicating surface upon said bed adapted to receive a sheet of paper; of a roller rotatably and slidably mounted on said duplicator adapted to depress a sheet of paper upon said duplicating surface, a second roller rotatably and slidably mounted on said duplicator, said second-named and first-named rollers cooperating with each other to automatically strip a sheet of paper from the said adhesive duplicating surface, and means provided on said duplicator adapted for receiving the sheet of paper after an impression has been made thereon and for carrying away the same.

18. In a duplicator, the combination with a supporting frame, a bed, and adhesive duplicating surface upon said bed adapted to receive a sheet of paper; of a roller rotatably and slidably mounted on said duplicator adapted to depress a sheet of paper upon said duplicating surface, and a second roller rotatably and slidably mounted on said duplicator, said second-named and first-named rollers cooperating with each other to automatically strip a sheet of paper from the said adhesive duplicating surface, and means mounted on said duplicator for preventing the free edge of the paper from coming in contact with the said duplicating surface, as the said paper is being stripped therefrom, said last mentioned means comprising a plurality of strips each having one end secured at a point adjacent the depressing roller and adapted to move therewith, and the other end thereof passing over the end of the supporting frame and having a counterweight carried thereby.

In testimony whereof I affix my signature.
FRANK A. ZIBELMAN.
